CONDITION RESPONSIVE CONTROL

George M. Hausler, Ballston Lake, N. Y., assignor
to General Electric Company, a corporation of
New York

Application September 26, 1941, Serial No. 412,415

13 Claims. (Cl. 200—83)

The invention relates to condition responsive control, particularly condition responsive control switches operable with a differential in response to variations in a predetermined control condition such as pressure, temperature or the like.

One of the principal objects is to provide an improved condition responsive switch calibrating mechanism with improved means for adjusting the differential of operation independently of the switch.

A more specific object is to provide an improved condition responsive variable differential calibrating mechanism for a switch unit having the principal operating parts of a reversely biased main and differential adjusting mechanism mounted in nested overlapping cooperating relation within a channel frame in cooperating relation with a movable calibrating scale and movable pointer, and having the switch unit mounted in parallel offset side-by-side alignment with the channel frame to enable the switch unit and its adjustable calibrating mechanism to be mounted on the opposite side of a base plate from the condition responsive operating device therefor so as to obtain a more accurate, compact and stronger mechanical construction. This is particularly advantageous where relatively heavy operating forces are encountered as for example in a steam pressure responsive control.

A more general object is to provide an improved condition responsive variable differential control calibrating mechanism whereby the different values of the control condition required to operate the control between two control positions may each be indicated directly on a movable calibrating scale and each adjusted at will.

Other objects and advantages of the present invention will become evident in the following description of the accompanying drawing in which Fig. 1 is a side view of a pressure responsive switch embodying the invention in a preferred form with the cover broken away more clearly to reveal the internal construction; Fig. 2 is a sectional view of the pressure switch taken from the end on the line 2—2; Fig. 3 is a sectional view of the pressure switch taken from the side on the line 3—3 and Fig. 4 is a sectional view taken from the top on the line 4—4.

In the improved construction, the base plate 10 is formed with an upturned rim 10a and with a pair of upwardly extending end plates 11, each provided with a knockout opening 12 for receiving the wiring conduit for the external circuit connections to be controlled by the switch. The removable enclosing cover 15, preferably formed

of moulded insulating material, has the internal ribs 17 engaging with the upturned rim 10a and is provided with suitable end openings 16 for receiving the end plates 11. Cover 15 is held in place by screw 18 which engages with the threaded socket 19 carried by the main channel frame adjustable differential calibrating unit 20 within which all of the parts of the switch calibrating mechanism are mounted in cooperating relation.

5 A window opening 21 is formed in the top of cover 15 in order to permit observation of the setting of the improved calibrating scale mechanism with which the channel frame adjustable differential calibrating unit 20 is provided as described hereinafter.

The main channel frame adjustable differential calibrating unit 20 is provided with corner lugs 22 which fit into corresponding slots formed in the base 10 in order to secure the frame accurately in proper position on the base by the screws 23. A pivot pin 27 extends across one end of the channel frame 20 for mounting the main L-shaped operating lever 28 with the longer arm 28a thereof extending in substantially parallel 10 spaced apart relation with the base 10 and with the shorter arm 28b extending upwardly at right angles. The main lever arm 28a is provided with the upturned stiffening side channels 29 with bearing openings therein for receiving the 15 pivot pin 27. The main lever arm 28a has an offset finger 30 extending through an opening 31 formed in one side of the channel frame 20 so as to move in the space under the auxiliary L-shaped mounting frame 35 which is secured to the base 10 and to the main frame 20 by means of lugs similar to lugs 22 and the screw 34.

A sealed snap switch mechanism 36 is mounted upon the auxiliary frame 35 with its operating pin 37 extending into operating relation with the finger 30 of the main operating lever 38. This sealed snap switch mechanism as shown is of the improved type described and claimed in the pending application, Serial No. 403,474, filed July 22, 1941, and assigned to the assignee of the present invention, although any other suitable type of snap switch mechanism may be employed, if desired.

In the snap switch mechanism 36, as shown, the operating pin 37 extends through the enclosing casing and operates the main pivoted switch operating lever 38 through the agency of the spring strip 39 carried by the main pivoted lever 38. The movable switch contact is carried on the main operating lever 38 so as to engage with a cooperating stationary contact when the main

lever 38 is in engagement with the adjustable stop 40. A permanent magnet 41 is provided for biasing lever 38 into engagement with stop 40 so as to effect snap action of the movable switch contact, to and from the circuit closing position. Since the detailed construction of the snap action switch mechanism itself is not of the essence of the present invention, no further description thereof is deemed necessary as any suitable form of snap switch may be employed.

The main L-shaped switch operating lever 28 is actuated by an operating pin 50 which extends through the opening 10b in base plate 10. Pin 50 in turn is operated by the pressure responsive bellows 52 enclosed within the sealed casing 53. The casing 53 is provided with a screw threaded connecting plug 54 for connection to a boiler or other source of pressure to which the bellows 52 is thus made responsive. A biasing force, opposing the action of bellows 52 on lever 28, is provided by the main pressure calibrating spring 60 which is secured at its ends to the threaded plugs 61, 62, the latter having an arm 62a extending upwardly through a slot 63 formed in the channel frame 20. A factory calibrating screw 65 extends through an opening formed in the end of the arm 28b into threaded engagement with the lug 61. A main pressure adjusting screw 66 extends through a cross bar 67 into threaded engagement with the plug 62. The cross bar 67 is mounted in the dovetailed slots 68 formed in the opposite legs of the channel frame 20 and is arranged to be locked in place by wedging apart the bendable portions 67a of the cross bar 67.

After the factory calibration is completed, the screw 65 is locked, preferably by soldering, so that all further adjustment of the tension of the spring 60 is accomplished by turning the screw 66 so as to vary the position of the threaded lug 62. Thus the biasing force of the main spring 60 will vary with the setting of the screw plug 62 and determine the pressure value at which the pivoted arm 28 is operated to move the snap action switch mechanism 36 to one of its controlled positions, namely, the circuit closing position.

The setting of the main calibrating spring 60 is indicated by stationary pointer 69 cooperating with the movable calibration scale 70 which slides in the upturned guides 71 formed in the top of the channel frame 20. The scale 70 is shown in Fig. 4 as calibrated for the pressure control range over which the pressure switch may be adjusted to operate and is moved by the arm 62a in accordance with the position of the screw plug 62 which, in turn, is determined by the adjustment of the main adjusting screw 66. In this way the lower limit of the pressure control range is always indicated by the stationary pointer 69 on the reciprocating pressure calibrated scale 70.

Differential adjustment

Variation in the operating differential of the mechanism is obtained by means of the complementary reversed overlapping L-shaped calibrating lever 75 which is provided with the enlarged opening 76c around the screw 66 and is pivotally mounted upon the pin 76 extending across the channel frame 20 adjacent the end opposite the main pivot pin 27. The differential adjusting lever 75 is provided with a rounded finger 77 at the end of the longer arm 75a so as to be in the path of and engage with the slightly raised platform 78 formed on the arm 28a of the main operating lever 28. However, when the arm 28a

is in the position shown in which the switch 36 is closed, the finger 77 is maintained out of engagement with the platform 78 due to the fact that the finger 78 laterally extending from arm 75a engages with the stop 80 provided in the side wall of the channel frame 20. The L-shaped differential lever 75 is biased into engagement with stop 80 by the differential adjustment spring 83 which is mounted in superimposed parallel relation with the main spring 60 inside of channel frame 20 in the space between the upturned arms of the two superimposed overlapping L-shaped levers 28 and 75. The differential calibrating spring 83, similarly to the main spring 60, is provided with the threaded plugs 84 and 85 at its ends. Plug 84 is in threaded engagement with the factory adjustment screw 86 which extends through a suitable opening adjacent the end of the shorter upright arm 75b of the differential calibrating lever 75 and the plug 85 is in threaded engagement with the differential adjustment screw 87. This differential adjustment screw 87 is mounted in the cross bar 88 which in turn is mounted in the dovetailed grooves 89 formed in the ends of the channel frame 20 and anchored in place in exactly the same way as the cross bar 67 by wedging apart the bendable sections 88a. After the proper factory differential adjustment is made, the factory adjusting screw 86 is locked in position, preferably by soldering. Thereafter adjustment of the differential spring 83 is accomplished entirely by turning the differential adjusting screw 87 so as to vary the position of the threaded lug 85 and thereby vary the tension exerted by the differential spring 83 on the differential lever 75.

The setting of the differential spring 83 is indicated by the movable pointer 90 which is carried by and extends upwardly from the threaded plug 85 through the slot 91 formed in the upper side of the channel frame 20 adjacent to the edge of the sliding scale 70, as shown more clearly in Fig. 4.

The relative proportions of all the parts are such that the joint action of the main pressure calibrating spring 60 and the differential spring 83 determine the pressure value required to effect operation of the snap action switch 36 from the closed position to the open position. This is due to the fact that the setting of the spring 60 alone determines the value at which the switch is operated to the closed position but the added force of differential spring 83 determines the pressure value at which the switch is operated to the open position. This switch opening pressure value is indicated directly on the movable scale 70 by the movable pointer 90, the position of which will vary in accordance with the adjustment of the tension of the differential spring 83. In this way the upper limit of the pressure control range is always indicated by the movable pointer 90 on the reciprocating pressure calibrated scale 70.

Operation

With the parts of the improved condition responsive control switch in their relative positions as shown, the contacts of switch 36 are closed and the operation is as follows:

When the pressure within casing 53 increases, the bellows 52 is compressed and moves the operating pin 50 upwardly thereby rotating the main lever 28 about the pivot pin 27 so as to raise the lateral extending arm 30 and thereby move the switch operating pin 37 upwardly to build up a force in the switch operating spring strip

39 tending to effect snap action operation of the switch contact from the closed position to the open position. During the initial movement of the main lever 28, only the main spring 60 opposes the operating force of the bellows 52, but as soon as arm 28 has moved upwardly a sufficient distance to engage the platform 78 with the finger 77, then the force of the differential spring 83 is added to that of the main spring 60 in opposition to the pressure exerted on the bellows 52. Thus the pressure must increase to a value sufficient to overcome both main spring 60 and differential spring 83, before the lateral finger 30 will move the pin 37 upwardly sufficiently to produce snap action opening of the switch 36. As previously explained, this switch opening pressure value is indicated directly on the scale 70 by the movable pointer 90.

With the snap action switch 36 in the open position, as soon as the pressure inside the casing 53 decreases, the combined forces of the main spring 60 and the differential spring 83, the latter operating through the differential lever 75, are effective to operate the main pivot lever 28 against the opposing force of the bellows 52 so as to lower the laterally extending arm 30. However, before the switch operating pin 37 has been lowered sufficiently to effect snap action operation of the switch 36 to the circuit closing position, the laterally extending arm 80 on the differential lever 75 engages with the stop 79 thereby preventing the force of the differential spring 83 from opposing the force of the bellows 52. Consequently the pressure within the casing 53 must then decrease to a value sufficiently low that the main spring 60 can move the platform 78 out of engagement with the finger 77 thereby lowering the laterally extending arm 30 sufficiently to permit snap action closure of the switch 36. Thus the closure of the switch is determined solely by the adjustment of the main spring 60, and the setting of the main spring 60 is indicated on the moving scale 70 by the stationary pointer 69.

The main adjusting screw 66 may be operated so as to move the scale 70 to the particular pressure value at which it is desired that the switch 36 be operated to the circuit closing position. The length of slot 63 limits this movement. Likewise the differential adjusting screw 87 may be rotated to move the pointer 90 so as to indicate the desired higher pressure value at which the switch 36 will be operated to the circuit opening position. The length and relative position of slot 91 limits this movement. It will be understood that, if desired, the switch 36 may be arranged to open its contacts at the pressure value determined by the adjustment of the main spring 66 and to close its contacts at the pressure value determined by the adjustment of the differential spring 87, if desired. Also other forms of condition responsive devices responsive to other conditions such as temperature, humidity, or other physical conditions, may be employed for moving the pin 50 of the operating mechanism without departing from the invention.

Thus, while I have shown and described my invention in considerable detail, I do not desire to be limited to the exact arrangements shown but seek to cover in the appended claims all those modifications that fall within the true spirit and scope of my invention.

What I claim as new and desire to secure by Letters Patent of the United States is:

1. A condition responsive control having in combination, a base plate with an opening formed therein, condition responsive means mounted on one side of said plate and having an operating member extending through said opening, a channel frame mounted on the opposite side of said plate to straddle said member and having an opening in one side thereof, an L-shaped main operating lever pivotally mounted within and adjacent one end of said channel frame with one arm thereof engaging said operating member to be operated thereby and having a finger extending laterally through said side opening in said channel frame, a reversed L-shaped differential control lever pivotally mounted within and adjacent the opposite end of said channel frame with one arm disposed in the path of the said one arm of said main lever, a pair of calibrating springs 20 reversely mounted within said channel frame in substantially parallel spaced apart alignment between the other arms of said L-shaped levers and each having one end thereof connected to a corresponding one of said other arms and 25 a tension adjusting element connected to the opposite end thereof, a calibrating scale element movably mounted on said channel frame and secured to and movable with the said tension adjusting element of said main lever calibrating spring, a stationary pointer mounted on said frame and cooperating with said movable scale member to indicate the calibration of said main lever calibrating spring, a second indicating pointer secured to and movable with the 30 said tension adjusting member of said differential lever calibrating spring for independently indicating the joint calibration thereof on said scale and a circuit controlling switch unit mounted on said base in off set side-by-side alignment with said channel frame and in operating relation with said laterally extending finger of said main operating lever.

2. A condition responsive control having in combination, a base plate with an opening formed therein, a condition responsive device having an operating member extending through said opening, a channel frame mounted on said plate to straddle said member, main lever pivotally mounted within and adjacent one end of said channel frame with said lever engaging said member to be operated thereby, a differential control lever pivotally mounted within and adjacent the opposite end of said channel frame and disposed in the path of said main lever, a pair of reversed parallel calibrating springs mounted within said channel frame and each having one end thereof connected to a corresponding one of said levers and a tension adjusting element connected to the opposite end thereof, a movable calibrating scale element secured to and movable with the said adjusting element of said main lever calibrating spring, a stationary pointer cooperating with said movable scale member to indicate the calibration of said main lever calibrating spring, a second indicating pointer secured to and movable with said tension adjusting member of said differential lever calibrating spring for independently indicating the joint calibration thereof on said scale and a circuit controlling switch mounted on said base to be operated by said main operating lever.

3. A condition responsive control having in combination, a condition responsive device having an operating member, a channel frame strad-

dling said member, a main lever pivotally mounted within and adjacent one end of said channel frame to be engaged by said member, a differential control lever pivotally mounted within and adjacent the other end of said channel frame and disposed in the path of said main lever, a pair of reversed parallel calibrating springs mounted within said channel frame and each having one end thereof connected to a corresponding one of said levers and a tension adjusting element connected to the opposite end thereof, a movable calibrating scale element secured to and movable with the said adjusting element of said main lever calibrating spring, a stationary pointer cooperating with said movable scale member to indicate the calibration of said main lever calibrating spring, a second indicating pointer secured to and movable with said tension adjusting member of said differential lever calibrating spring for independently indicating the joint calibration thereof on said scale and a circuit controlling switch operated by said main operating lever member.

4. A condition responsive control having in combination, a condition responsive device having a main movable control member operated thereby between two control positions, a movable differential control member disposed in the path of said main control member between said positions, a separate calibrating spring for each member, each spring having one end thereof connected to the corresponding member and a tension adjusting element connected to the opposite end thereof, a movable condition calibrated scale element secured to and movable with the said tension adjusting element of said main calibrating spring, a stationary pointer cooperating with said movable scale member to indicate the value of the condition to which said device is responsive required to effect operation of said main control member to one of said positions, and a second indicating pointer secured to and movable with said tension adjusting member of said differential calibrating spring for independently indicating on said scale the value of the condition to which said device is responsive required to effect operation of said main control member to the other of said positions.

5. A condition responsive control having in combination, a condition responsive element, variable differential control means operated by said element upon variation in the condition to which said element is responsive over an operating range having variable limits, a range calibrating spring for said control means, a differential calibrating spring for said control means, each of said springs having an adjusting member, a movable calibrating scale element connected for movement with the said adjusting element of said range spring, a pointer cooperating with said movable scale member to indicate one limit of the operating range of said control means, and a movable indicating pointer connected for movement with said adjusting member of said differential spring for independently indicating the other limit of the operating range of said control means on said scale.

6. A condition responsive device having in combination condition responsive operating means, switching means operated by said responsive means between two positions upon variation in the condition to which said operating means is responsive over an operating range having variable limits, a pair of adjustable biasing means, one of said biasing means acting on said

condition responsive means with said switching means in one position and both of said biasing means acting on said responsive means with said switching means in the other position, and calibrating means including a stationary pointer and a cooperating movable scale connected to be moved in accordance with the adjustment of said one biasing means for indicating one limit of the operating range of said operating means and having a movable pointer cooperating therewith and connected to be moved in accordance with the adjustment of said other biasing means for indicating the other limit of the operating range of said operating means.

7. A condition responsive device having in combination condition responsive operating means, a movable control member operated thereby between two positions upon variation in the condition to which said operating means is responsive over an operating range having variable limits, means including a pair of adjustable biasing means for varying said limits, one of said biasing means acting on said condition responsive means with said member in one of said positions and both of said biasing means acting on said responsive means with said member in the other of said positions, and calibrating means including a stationary pointer and a cooperating movable condition calibrated scale connected to be operated in accordance with the adjustment of said one biasing means for indicating one limit of the operating range of said operating means and having a movable pointer cooperating therewith and connected to be moved in accordance with the adjustment of said other biasing means for indicating the other limit of the operating range of said operating means.

8. A condition responsive device having in combination a channel frame, a pair of L-shaped levers mounted within said channel frame in reversed overlapping relation with one arm of one of said members disposed in the path of movement of the corresponding arm of the other of said levers, a pair of reversed parallel calibrating springs mounted within said channel frame in the space between the other arms of said members, and each having one end thereof connected to a corresponding one of said other arms, a pair of adjusting means each connected with the other end of a corresponding one of said springs, a condition responsive device having an operating member engaging said one arm of said one lever, and a switch mounted to be operated by said one arm of said one lever to one position in accordance with the bias of one of said springs and to a second position in accordance with the bias of both of said springs.

9. A condition responsive device having in combination a pair of L-shaped levers mounted in reversed overlapping relation with one arm of one of said members disposed in the path of movement of one arm of the other of said levers, a pair of reversed parallel calibrating springs mounted in the space between the other arms of said members, and each having one end thereof connected to a corresponding other arm of said levers, separate adjusting means connected with the other end of each spring, a condition responsive device having an operating member engaging said one lever, and a switch mounted to be operated by said one lever to one position in accordance with the bias of one of said springs and to a second position in accordance with the bias of both of said springs.

10. A condition responsive device having in

combination a channel frame having a bar extending across each end thereof, a pair of springs mounted within said channel frame and each adjustably connected with a corresponding bar, a pair of L-shaped levers pivotally mounted within said channel frame in reversed overlapping relation and each connected with a corresponding spring, condition responsive means for operating one of said levers into engagement with the other lever, and a switch mounted to be operated by said one lever to one position in accordance with the adjustable bias of the corresponding spring and to a second position in accordance with the adjustable bias of both of said springs.

11. A condition responsive device having in combination a base provided with an opening, a channel frame calibrating unit mounted on one side of said base to straddle said base opening and having an opening in one side thereof, lever mechanism pivotally mounted within said frame and having a finger extending through said side opening, a condition responsive device mounted on the opposite side of said base and having an operating member extending through said base opening for operating said lever mechanism, and a switch mounted on said base adjacent said one side of said channel frame to be operated by said finger.

12. A condition responsive device having in combination a channel frame calibrating unit provided with an opening in one side thereof, lever mechanism pivotally mounted within said frame and having a finger extending through said opening, a condition responsive device having a movable operating member extending between the edges of said channel for operating said lever mechanism, and a switch mounted at said one side of said channel frame to be operated by said finger.

13. In combination, a variable differential condition responsive control device having a differential adjusting screw and a separately operable control range adjusting screw disposed in parallel alignment, a reciprocating calibrated control range scale having a threaded driving element operated by said range adjusting screw, a stationary pointer disposed at one side of said scale for indicating thereon one limit of the control range of said device, and a movable pointer having a threaded driving element operated by said differential adjusting member for moving said pointer along the other side of said scale to indicate thereon the other limit of said control range.

GEORGE M. HAUSLER.
